GENTRY CASH, OF WHITING, INDIANA, ASSIGNEE TO STANDARD OIL COMPANY, OF WHITING, INDIANA, A CORPORATION OF INDIANA

ART OF CONVERTING HIGH BOILING HYDROCARBON OILS INTO LOWER BOILING HYDROCARBON OILS

Application filed July 13, 1927. Serial No. 205,316.

The present invention relates to improvements in the art of converting high boiling hydrocarbon oils into lower boiling hydrocarbon oils, such as gasoline, and will be fully understood from the following description thereof, illustrated by the accompanying drawing, wherein apparatus suitable for carrying the invention into effect is illustrated diagrammatically in section.

10 Referring more particularly to the drawing, the numeral 5 indicates diagrammatically a furnace setting, wherein is mounted a continuous coil 6, heated by any suitable heating means, for example, the burner 7. This 15 coil is diagrammatically illustrated; it is to be noted in connection therewith, however, that the portion last traversed by the oil is, in the form shown, that directly exposed to the radiant heat of the flame and is indicated by 20 the numeral 6^a. From the outlet of the coil 6, a line 7 leads to the two enlarged chambers 8, being provided with the valved connections 9 leading into the latter. The enlarged chambers 8 are provided with means for preventing 25 any substantial drop in temperature below the outlet temperature of the oil leaving the coil 6. In the form illustrated, this is effected by providing around the chambers 8 a setting 10, in which a heated gaseous atmosphere 30 is maintained by means of the small burners 11. By this means the chambers 8 are surrounded by an insulating blanket of hot gases which may be as hot as or slightly hotter than the oil contained therein. It is readily understood 35 that other means for preventing substantial temperature drops may be employed, for example, a suitable insulating lagging surrounding the chambers.

The chambers 8 are illustrated as comparatively elongated vertical cylinders. From the upper portion thereof vapor lines 12 are provided which lead to the manifold 13. The latter is connected by the pipe 14 with the lower portion of a dephlegmating tower 15, 45 within which fractionating plates 16 of any suitable type are provided. In the upper portion of the dephlegmating tower 15 suitable cooling means, such as the coil 17, are provided. Uncondensed vapors pass out of the 50 dephlegmating tower 13 through the vapor

line 18 which leads to any suitable condensing and pressure maintaining devices.

Means, such as the valved discharge pipes 19, are provided for the withdrawal of tar or unvaporized liquid products from the lower 55 portions of the chambers 8.

Liquids condensed in the dephlegmating tower 15 are withdrawn through pipe 20 by pump 21 and forced through the pipe 22 into the later portion of the coil 6, and in the form 60 illustrated, in that portion 6^a which is directly exposed to the radiant heat of the flame. A stream of oil to be converted is fed to the coil 6 through the line 23 by any suitable means.

In operation, the oil to be converted, which is preferably a distillate stock of the character of gas oil and may contain products which have previously been subjected to pressure cracking conditions, is forced by 70 any suitable means through the line 23 into and through the coil 6. In the coil 6, the oil is brought to conversion temperatures above 700° F. and preferably to 800° F. or higher. At a point in the coil at which the oil stream 75 flowing therethrough has attained a cracking temperature, and preferably in the later portion of the coil exposed to radiant heat of the flame, the cooler reflux condensate formed in the dephlegmating tower 15 is forced into 80 the stream of oil and carried with it. In normal operation upon a stock of approximately gas oil gravity, the proportion of liquid thus supplied may be 1 to 1.5 times the volume (cold) of the oil fed into the coil 85 through the line 23. The mixed oils at conversion temperature are discharged through the line 7 into the stills 8, through which they may flow in series or in parallel. In the form illustrated, parallel flow into the 90 stills is employed. In the stills 8 conversion temperatures equal to or somewhat below the temperature of the oil at the outlet from the coil 6 are maintained. For example, the temperature at the outlet of the coil may be 830 95 to 850° F. and that maintained within the chambers 8 from 750 to 800° F. A pressure in excess of 4 atmospheres, and preferably of 20 atmospheres or higher is maintained within the chambers 8.

The vapors evolved from the oil and separated in the chambers 8 are discharged through the pipes 12 into a manifold 13 and pass through line 14 into the dephlegmating 5 column 16, in which the vapors of conversion products of higher boiling point range than the desired gasoline-like products are condensed by the passage of a suitable cooling medium, such as oil to be subjected to the 10 conversion process, through the coil 17. The reflux condensate, which is highly heated, say at 650 to 680° F., is withdrawn through the line 20 and forced by the hot oil pump 21 through the line 22 and to the later portion 15 of the coil 6, as hereinbefore described.

In operations as hitherto conducted, it has been customary to introduce the reflux condensate into the stream of fresh oil passing through the furnace in which the latter is 20 brought to conversion temperature at approximately the beginning of the coil or at some comparatively early intermediate point before the oil has attained a conversion temperature. By carrying out the operation as 25 hereinbefore described, introducing the reflux into the later portion of the coil at a point at which the oil stream has attained a conversion temperature, it has been found that the capacity of a given unit or piece of 30 apparatus may be very substantially increased, in some cases, practically doubled, without decreasing efficiency or substantially affecting the rate of conversion in the unit. Furthermore, the introduction of the reflux 35 condensate in the manner described so greatly increases the rate of flow and the heat transfer in the later portion of the coil that it is possible and effective to subject the mixed stream of oil thereafter to the full 40 radiant heat of the flames, suitably simultaneously with the heat of the combustion gases.

Although the present invention has been described in connection with the specific details of a procedure for carrying it into effect, it is not intended that these details shall be regarded as limitations upon the scope of the invention, except in so far as included 45 within the accompanying claim.

50 I claim:

The method of effecting conversion of hydrocarbon oils into lower boiling hydrocarbon oils such as gasoline, which comprises passing the hydrocarbon oils to be converted 55 in a continuous stream through a heating zone in which they are brought to conversion temperature and are subsequently passed through a portion of the heating zone in which they are subjected to the direct radiant heat of the flame, separating from the heated oil products leaving the heating zone 60 vapors of converted products including the desired low boiling products, cooling the separated vapors to condense and remove 65 therefrom products heavier than gasoline as

a reflux condensate, and forcing the reflux condensate while hot directly into the flowing stream of oil in the heating zone at a single point after the oil reaches cracking temperature and as it enters the portion of 70 the heating zone subjected to the greatest radiant heat of the flame.
